UNITED STATES PATENT OFFICE.

JOHN ERICKSON, OF CHICAGO, ILLINOIS, ASSIGNOR, BY MESNE ASSIGNMENTS, TO
ROCHESTER H. ROGERS, OF ROCHESTER, NEW YORK.

CONNECTOR REPEATER-SWITCH OF AUTOMATIC TELEPHONE-EXCHANGES FOR HANDLING FIRE-ALARM CALLS.

1,228,007.

Specification of Letters Patent.

Patented May 29, 1917.

Application filed February 25, 1914, Serial No. 821,097. Renewed April 24, 1916. Serial No. 93,306.

To all whom it may concern:

Be it known that I, JOHN ERICKSON, of Chicago, in the county of Cook and State of Illinois, have invented certain new and useful Improvements in the Connector Repeater-Switches of Automatic Telephone-Exchanges for Handling Fire-Alarm Calls; and I do hereby declare the following to be a full, clear, and exact description of the same, reference being had to the accompanying drawings, forming a part of this specification, and to the reference-numerals marked thereon.

My present invention has for its object to provide certain improvements in the arrangement, adjustment and means of operating the connector repeater switch of an automatic telephone exchange system which is used for the transmission of the impulses of current employed for actuating the fire alarm signal-recording mechanism at the fire department headquarters after the connection with said circuit has been established through the various selector switches which are employed for connecting through the central office or exchange the subscriber's circuit on which the call is initiated. To these and other ends the invention consists in certain improvements and combinations of parts, all as will be hereinafter more fully described, the novel features being pointed out in the claims at the end of the specification.

In the drawings:

The figure is a diagrammatic illustration showing a subscriber's line circuit equipped with a signal mechanism and indicating said circuit extended through the first, second and third selector switches to the repeater switch embodying the present invention as used in practice in a large exchange.

Similar reference numerals throughout the several structures indicate the same parts.

The invention will best be understood by a brief description of the difficulties encountered in attempting to operate fire alarm signals over an automatic telephone exchange system in which the subscribers set up their desired connections by means of an impulse transmitting mechanism comprising a dial A which the operator adjusts by imparting thereto a partial revolution and which, when released, will transmit one

or more impulses which control the operation of the central office switches. The dial may be adjusted to the limit of its movement so that when released it will despatch ten impulses in regular succession and if moved a shorter distance it will despatch nine, eight, etc. impulses or only one impulse. In an automatic telephone exchange of one thousand lines or under the connections between any two subscriber's circuits will be effected by the use of one selector and one connector switch, and in larger exchanges the number of selectors is increased, although the operation of the additional switches is the same, the call being received in the first selector, transmitted by it to a second selector, thence to the third selector and eventually to the connector. A detailed description and construction of these switches and their operation is not required because of the general knowledge of these mechanisms possessed by those skilled in the telephone art, although for convenience as a means of reference on this subject I would mention the patents granted jointly to myself, Charles J. Erickson and Alexander E. Keith for automatic telephone connector and selector switches, Nos. 815,176 and 815,321, respectively, issued March 13, 1906, which disclose generally the arrangement of the banks of contacts, and the rotary and vertically movable shafts carrying the wipers co-operating with said contacts, although it will be understood, of course, that the electromagnetic operating devices by which these movements are effected may be changed to suit various conditions of service.

These central office automatic switches when actuated to connect a subscriber's circuit with the fire alarm circuit leading to fire department headquarters are not controlled in their movements by the dial A but by the alarm signal box mechanism, and the purpose of my invention, as will herein-after appear with greater particularity, is to so arrange the alarm box mechanism and the switching apparatus that, in the event a subscriber erroneously endeavors to establish connection with the fire department headquarters by the operation of the dial A, either by accidentally calling the wrong number or by a premeditated attempt to establish such a connection, the switches over

which the call is initiated, will be knocked down or released as soon as the circuit is connected through to the connector repeater switch.

5 The primary difficulty which has been encountered heretofore is due to the fact that telephone subscribers or operators in establishing connections through the various switches would, through error in the operation of the dial A cause the switches at the central office to set up a connection with the fire alarm circuit with the result that upon the subsequent rotation of the dial in an attempt to complete the number of the station they intended to call would cause the actuation of the signal gong and register of the fire department headquarters. For instance, if the last digit of the number called was "5" a corresponding number of 10 strokes would be imparted to the gong and register giving what would otherwise be termed a "false alarm."

These difficulties I have been able to eliminate by connecting the fire alarm circuit to 25 the last set of contacts in the row of contacts on the connector switch; making all the other contacts "busy," and so mounting the wipers on the connector shaft that in order to reach the fire alarm circuit contacts it is 30 necessary that the rotary movement imparted to said shaft shall be at least one step more than is ordinarily required, *i. e.* if the connector switch is provided with ten sets of contacts in a row, then I would adjust the 35 wipers so that eleven or more steps would be required to be imparted to the rotary shaft to bring said wipers into engagement with the last set of contacts. Therefore, ten steps or anything less than this number of movements caused by the operation of the dial A would effect the release of the connector repeater switch automatically in the usual manner by which said release is effected, but as the signaling box B is capable of transmitting eleven or more impulses it is possible, therefore, to arrange the apparatus so that the wipers of the connector switch can only be moved into engagement with the last set of contacts by the movement of said 50 box mechanism.

As a type of signal box mechanism which may in part be utilized for actuating the automatic switches, reference is made to Patent No. 958,719, issued May 24, 1910, to F. S. 55 Bronson, for signal box for fire alarm system, and to my pending application, Renewal Serial No. 793,470, filed October 4, 1913. This mechanism comprises an arbor B' carrying a switch actuating wheel C and a code wheel D, the former being provided with the necessary grooves or notches whereby circuit contacts are opened and closed to successively actuate the selector switches and finally the connector repeater switch, 60 and the latter is provided with other sets of

notches which control the transmission of impulses over the circuit previously established to transmit to the fire alarm headquarters the code signal of this particular alarm despaching mechanism. In the figure the wheel C is shown provided with three groups of notches consisting respectively of three, nine and eleven notches corresponding to the directory number 3-9-11 which would be assigned to the telephone fire alarm circuit if it was intended that the circuit should be established manually. The first two groups of notches serve to extend the subscriber's telephone line through the first and second selectors, and the third group of eleven notches effects a corresponding number of steps of the wipers of the connector repeater switches to complete the connection of the subscriber's circuit with the fire alarm circuit, after which the code signal is despached by impulses sent over the line by opening and closing the contacts controlled by the wheel D.

In order to illustrate my invention in detail I have shown the connector switch mechanism in its simplest form, many of the parts required in actual service being omitted. The rotary shaft, as indicated by S, carries the three wipers s' s^2 and s^3 which coöperate with the three rows of horizontal contacts. The rotary movement of the shaft is caused by the rotary magnet R arranged in a circuit composed of wires r , r' , over which the rotary impulses are imparted by the eleven notches or recesses c on the wheel C. The trunk or circuit leading to the fire alarm headquarters comprises the wire f connected to the last terminal in the upper row which is engaged by the wiper s' when the latter takes its last step. With the parts in this position they are then closed to ground the wire f' leading to contact f^2 which is engaged by contact f^3 grounded over the wire f^4 . This pair of contacts f^2 and f^3 are on the line relay L which is energized by reason of the closing of the subscriber's circuit.

The release of the switch is effected by disengaging the holding pawl of the shaft S which is caused by the energizing of the release magnet T, the circuit of which is extended through contacts on two slow operating relays U and V as well as a contact on the line relay L whereby the shaft S is released automatically upon any interruption occurring in the transmission of the last group of impulses and also by the act of opening the subscriber's circuit after the alarm impulses have been transmitted. This circuit may be traced from battery lead X' to wire t , relay T, wire t' , contacts t^2 , t^3 on relay V, 120 wire t^4 , to wiper s^3 . The release wire t^5 leads from the last contact t^5 of the bottom row of contacts to the normally closed springs t^1 , t^2 on relay U, the last mentioned spring being tied by the wire t^6 to the con- 130

tact t^{10} on the line relay L, which last mentioned contact is grounded when the spring f^3 engages therewith. It will be understood that the line relay L is energized with each 5 impulse of current despatched over the subscriber's circuit and that it is the movement of the armature of this relay that causes the step by step movement of the rotary magnets R and the shaft S and consequently the 10 spring f^3 alternately engages the contacts f^2 and t^{10} , the latter furnishing the ground over which the release of the switch shaft S is effected, but that this release does not occur while the impulses are being transmitted 15 regularly at a predetermined rate because of the slower action of the relays U and V, the residual magnetism of which holds said release circuit open momentarily while the switch wipers are stepping from one contact 20 to another.

Now in order that the connector switch may be released automatically in the event a subscriber accidentally picks up this circuit and, further, to require said switch to 25 be operated by eleven or more impulses, the first nine contacts of the lower row are joined together, as indicated by w and are also connected to the first contact y of the middle row. It will be noted that the wipers 30 s' and s^3 are set on a shaft S in such position that they do not engage the first contact of their respective rows of terminals upon the first step or movement of the shaft S, but that middle wiper s^2 does engage the first 35 contact y in readiness to transmit the release impulse in the event the wipers are not further advanced. Upon the second movement of the wipers s' , s^2 , s^3 the last mentioned wiper engages the first contact of its row 40 and as all of these contacts with the exception of the last one are connected with ground over the wire W the release will be effected if the switch is allowed to stop in any one of the first ten positions since ten 45 is the greatest number of impulses that can be despatched by the subscriber's sending impulse mechanism A. The result described might be accomplished without offsetting the wipers s' , s^3 with relation to the middle 50 wipers s^2 , but this would require making the switches with eleven or more contacts in each row and it will, therefore, be seen that the scheme that I have suggested of offsetting the wipers is that all of the parts can 55 be made to conform to switch mechanism in use at the present time. In other words, I am enabled to carry out my invention by the use of the standard type of apparatus.

The circuit of the release magnet T must 60 be closed at contact of springs t^2 and t^3 after the wiper S^3 has reached the contact t^6 , leaving it in readiness for the release of the connector repeater switch after the fire alarm impulses have ceased. When the 65 wiper S' reaches the last contact and the

wiper S^3 reaches contact t^6 there is an interval of time when the subscriber's circuit is closed prior to the switching of the control to the box number wheel D. The circuit is at once established from battery, 70 wire f^4 , contacts f^3 , f^2 , wire f' , switch arm S' , wire f , relay M to battery lead X'. This energizes relay M breaking contacts m^2 , m^3 , thereby deenergizing relay V, closing contacts t^2 , t^3 , which thereby completes the circuit to the release magnet T with the exception of holding it open at contacts t^{10} and f^3 75 of relay L. After the completion of the fire alarm call, the subscriber's line is opened, deenergizing relay L, closing its contact, thereby energizing release magnet T restoring the switch to normal position.

At the time the switch is first established in reaching the adjusted position of switch arm S' and S^3 a circuit is established from 85 ground, wire f^4 , contacts f^3 , f^2 , wire f' , arm S' , wire f , to the magnet Z controlling the recording apparatus Y at fire headquarters.

The operation of the release magnet T is prevented while the switch arm S^3 is being 90 stepped around by the opening of the circuit of said magnet at the contacts t^2 , t^3 by energization of the relay V, over a circuit leading from battery lead X', and connected to the wire r' , the result being that rotary 95 magnet R and relay V are connected in multiple and, therefore, relay V is continually energized while rotary magnet is receiving impulses, due to the fact that the relay V is slow acting. The circuit of the release magnet T must be opened after the wiper S^3 has reached the contact t^6 , so that 100 impulses from ground over the wire t^6 may be transmitted after the cessation of impulses through line relay L, which is accomplished by providing a relay M in a circuit connected on one side to battery lead X' and on the other to wire f , leading from the last contact on the bank traversed by switch arm S' . When said switch stops in 105 the last position the relay M is energized, thereby breaking a pair of contacts m^2 and m^3 interposed in wire r' of the circuits of relay V and rotary magnet R.

This results in restoring the circuit of the 115 magnet T at the contacts t^2 , t^3 in readiness for a release impulse when the fire alarm impulses have ceased, and interrupts passage of current to the rotary magnet R. From the foregoing it will be seen that upon 120 the transmission of the eleven impulses in the group of impulses the wipers s' and s^3 are finally landed on the last terminals in their respective rows of contacts so that the subscriber's circuit has no real connection 125 with the trunk circuit leading to fire headquarters and by the operation of the line relay L, due to the impulses from wheel C, impulses are despatched over the trunk to the recording apparatus at fire headquarters. 130

At the same time the back release circuit is established so that the connector repeater switch stands in its adjusted position until the subscriber's circuit is opened upon the completion of the transmission of a fire alarm signal. The opening of the subscriber's circuit deenergizes line relay L, making contact of springs t^{10} and f^8 closing a circuit from ground to wire t^4 , contact f^8 , 5 contact t^{10} , wire t^9 , contact t^8 , contact t^7 , (relay U is deenergized by reason of having its circuit opened by the opening of contacts f^2 and f^8) wire t^5 , contact t^6 , switch arm S^3 , wire t^4 , contacts t^8 , t^2 , wire t' , release magnet T, wire t to battery lead X'. This energizes release magnet T, restoring 10 the switch to its normal position.

I claim as my invention:

1. The combination with an automatic telephone exchange system comprising a subscriber's circuit provided with a manual impulse transmitter adapted to despatch impulses limited to a given maximum number, and automatic switches controlled by said 20 impulses, of an alarm impulse transmitting mechanism associated with said subscriber's circuit adapted to transmit current impulses of a number greater than the maximum number which may be despatched by the manual transmitter, a connector switch comprising coöperating wipers and contacts and means for driving the wipers in accordance with the current impulses when actuated by a number of impulses less than the 30 total transmitted by the alarm transmitter, and an alarm trunk leading from the contacts of the switch upon which the wipers rest after being advanced.
2. In an automatic alarm apparatus for 40 an automatic telephone exchange system, the combination with subscriber's lines equipped with manual impulse transmitters capable of despatching impulses of a given maximum number and automatic switches for connecting said lines and an alarm impulse transmitting mechanism capable of despatching impulses of a greater total number than said manual mechanism, of a connector switch adapted to be actuated by 50 said impulses, comprising coöperating wipers and contacts, means for advancing the wipers, and devices for restoring them to normal upon cessation of the transmission of current impulses less in number than the 60 total number of those despatched by the alarm transmitter and an alarm trunk circuit leading from the terminals of said switch upon which the wipers rest at the limit of their movement.
3. In an automatic alarm apparatus for 65 an automatic telephone exchange system, the combination with subscriber's lines equipped with manually operated impulse transmitters capable of transmitting a maximum number of ten current impulses and

an alarm impulse transmitter adapted to despatch eleven such impulses, of automatic switches for connecting the subscriber's lines comprising a connector switch having coöperating wipers and contacts and a release mechanism adapted to be automatically actuated upon the arresting of the wipers in any of the first ten positions and an alarm circuit leading from the contacts engaged by the wipers in their eleventh position of movement having alarm apparatus thereon.

4. In an automatic alarm apparatus for an automatic telephone exchange system, the combination with subscriber's lines equipped with manually operated impulse transmitters capable of transmitting a maximum number of ten current impulses, an automatic alarm impulse transmitter adapted to despatch a greater number of such impulses, and an alarm circuit provided with alarm apparatus, of an automatic switch mechanism having coöperating wipers and contacts and rotary driving devices actuating the wipers one step for each 80 impulse transmitted by either of the transmitting mechanisms and also provided with release devices for restoring the wipers to their normal position, said release devices being adapted to be automatically operated upon the cessation of impulses which leave the wipers in any one of their first ten steps, but which are capable of operation in the usual manner by line control upon the eleventh or subsequent steps, and an alarm circuit leading from terminals with which the wipers engage when allowed to rest after the tenth step.

5. A connector switch for use in transmitting alarm impulses over the lines of 105 automatic telephone systems comprising a bank of contacts arranged in a plurality of rows one of which comprises ten contacts, a set of line and release wipers, means for advancing the latter step-by-step into 110 engagement with said contacts, said contacts and wipers being so positioned relatively to each other when the wipers are in the normal position that one step is required to position the release wiper in engagement with the first contact and eleven 115 steps are required to place the line wiper in engagement with the tenth contact.

6. The combination with an automatic telephone exchange system, including a subscriber's circuit provided with a manual, impulse transmitter for despatching impulses over said circuit, of an alarm impulse transmitting mechanism associated with said subscriber's circuit adapted to 120 transmit current impulses, and a connector repeater switch capable of being set by the impulses of the alarm impulse transmitting mechanism and incapable of being set by the manual impulse transmitter aforesaid. 130

7. The combination with an automatic telephone exchange system, including a subscriber's circuit provided with a manual impulse transmitter for despatching impulses, of an alarm impulse transmitting mechanism associated with said subscriber's circuit adapted to transmit current impulses, and a connector repeater switch including coöperating wipers and contacts being capable of operation to a predetermined position by the impulses despatched by the alarm impulse transmitting mechanism and incapable of operation to such predetermined position by the impulse from the manual impulse transmitter aforesaid.
8. The combination with an automatic telephone exchange system including a subscriber's circuit provided with a manual impulse transmitter for despatching impulses, of an alarm impulse transmitting mechanism associated with said subscriber's circuit and adapted to transmit current impulses, and a connector repeater switch including wipers and contacts capable of being relatively set for a predetermined co-operation by the impulse despatched by the alarm impulse transmitting mechanism and incapable of being so set by the impulse from the subscriber's manual impulse transmitter.
9. In an automatic telephone exchange system including a subscriber's circuit pro-

vided with a manual impulse transmitter capable of transmitting a maximum number of impulses, of a connector repeater switch cooperating with said subscriber's line circuit and incapable of being set by the maximum or less number of impulses transmitted by the manual impulse transmitter, and means independent of said manual impulse transmitter for operating said switch by despatching impulses over the subscriber's circuit in excess of the maximum number of impulses capable of being despatched by said manual impulse transmitter.

10. In an automatic telephone exchange system including a subscriber's circuit provided with a manual impulse transmitter capable of transmitting a maximum number of impulses, of a connector repeater switch incapable of being set by the maximum or less number of impulses transmitted by the manual impulse transmitter, and means associated with the subscriber's circuit for transmitting impulses in excess of the maximum number transmitted by the manual impulse transmitter for setting the switch aforesaid.
